Fig. 5.

FIG. 6.

A technical drawing of a mechanical assembly. The top part shows a horizontal beam with a hatched cross-section. Below it, a vertical frame is supported by two vertical posts. A horizontal rod with a central slot passes through the frame. Two vertical plates, labeled 'B', are attached to the frame. A central vertical plate, labeled 'C', has a slot that aligns with the central slot in the horizontal rod. A small rectangular component, labeled 'D', is positioned between the central vertical plate and the top horizontal beam. A horizontal slot, labeled 'F', is located in the lower part of the central vertical plate. A small rectangular component, labeled 'E', is positioned below the horizontal slot 'F'. The bottom part of the drawing shows a horizontal beam with a hatched cross-section, supported by two vertical posts. A horizontal rod with a central slot passes through the frame. Two vertical plates, labeled 'B', are attached to the frame. A central vertical plate, labeled 'C', has a slot that aligns with the central slot in the horizontal rod. A small rectangular component, labeled 'D', is positioned between the central vertical plate and the top horizontal beam. A horizontal slot, labeled 'F', is located in the lower part of the central vertical plate. A small rectangular component, labeled 'E', is positioned below the horizontal slot 'F'.

UNITED STATES PATENT OFFICE.

JAMES S. SIMONTON, OF HOOD RIVER, OREGON.

FOLDING AND CONVERTIBLE TABLE.

1,069,483.

Specification of Letters Patent.

Patented Aug. 5, 1913.

Application filed December 17, 1912. Serial No. 737,207.

To all whom it may concern:

Be it known that I, JAMES S. SIMONTON, a citizen of the United States, and a resident of Hood River, in the county of Hood River 5 and State of Oregon, have made certain new and useful Improvements in Folding and Convertible Tables, of which the following is a specification.

My present invention relates generally to 10 tables, and more particularly to a combined folding and convertible table, that is, a table which may be folded and unfolded and when in the latter position may be adjusted to the ordinary height and to a lesser height where- 15 by to form a lap-board.

The primary object of my invention is to 20 provide a table capable of performing functions such as outlined, the folding and adjustment of which may be readily and easily accomplished, and which will be strong and durable and comparatively inexpensive.

In the accompanying drawings, forming a 25 part of this specification, Figure 1 is a vertical longitudinal section through my im- proved table in the operative position, and 30 extended to the usual height. Fig. 2 is a similar view illustrating the table adjusted to a lesser height for use as a lap-board. Fig. 3 is a vertical cross section taken sub- 35 substantially on the line 3—3 of Fig. 1. Fig. 4 is a longitudinal section illustrating a part 40 of the table in the folded position. Fig. 5 is a bottom plan view of the folded table as 45 shown in Fig. 4, and Fig. 6 is a view similar 50 to Fig. 3, taken substantially on the line 55 6—6 of Fig. 1.

Referring now to these figures, my im- 60 proved table comprises a solid top A, to the under surface of which are secured the trans- 65 verse cleats a , which are arranged adja- 70 cent opposite ends of the table top and are 75 provided with depending ears a' through 80 which are secured the transverse rods a^2 85 and a^3 .

The rods a^2 and a^3 , respectively, 90 form hinge connections for the upper or sup- 95 plemental leg frames B and B', through 100 which the said rods pass, the 105 said supplemental leg frames embodying 110 side bars at an intermediate point through 115 which are connected rods b and b' . The 120 rods b , b' pass loosely through spaced par- 125 allel connecting beams C and C', which thus 130 connect the supplemental leg frames B and 135 B' in such a manner that movement of these 140 leg frames upon their hinge connections a^2

and a^3 must be in the same direction. Adja- 145 cent the leg frame B' the connecting beams 150 C and C' support a transverse rod c , which 155 rod is adapted to receive the recessed end d 160 of a latch bar D, the opposite of which is 165 hingedly connected at d' to the under sur- 170 face of the table top A. Thus when the 175 supplemental legs are extended outwardly 180 in the position as shown in Fig. 1, the latch 185 bar D may be utilized to maintain the 190 frames in such position, release of this latch 195 bar permitting the said leg frames to be 200 swung in the same direction against the un- 205 der surface of the table top in a position as 210 clearly indicated in Fig. 2.

The intermediate rods b and b' also pass 215 loosely through the upper ends of the side 220 bars of the main leg frames E and E' respec- 225 tively, the side bars of these main leg frames 230 being connected at intermediate points by 235 transverse strips e and e' upon which the 240 notched ends of a longitudinal bracing or 245 supporting bar F are adapted to engage 250 when the said leg frames are extended as 255 shown in Fig. 1. This bar F is carried by 260 a hanger F', one end of which is integrally 265 connected at f to a point intermediate the 270 said bar F, and the opposite end of which 275 is mounted upon the intermediate rod b of 280 the supplemental leg frame B. The ends of 285 the bar F may also have swiveled hooks f' 290 adapted for movement to engage beneath the 295 transverse strips e and e' and particularly 300 shown in Fig. 1, in order to lock the mem- 305 bers in position. Thus from the foregoing 310 the parts may be readily folded to assume 315 the positions as shown in Figs. 4 and 5. 320 Should it be desired to adjust the table for 325 use as a lap-board, the main leg frames 330 E and E' are moved to a position at right 335 angles with respect to the table top A upon 340 the pivots b and b' and the bar F is ex- 345 tended and locked in connection with the 350 main leg frames, through the means pre- 355 viously described and as particularly shown 360 in Fig. 2. On the other hand, should it be 365 desired to adjust the table for ordinary use, 370 the supplemental leg frames B and B' are 375 also moved to an angular position with re- 380 spect to the table top and the latch bar E 385 extended outwardly to engage the trans- 390 verse rod c of the connecting bars C and C'. 395 This locks the supplemental leg frames in 400 position, and in order to further guard 405 against their movement and to provide a 410 rigid structure, the supplemental leg frame

415

B may be provided with a transverse strip b^2 , the ends of which engage the upper bar ends of the bars of the main leg frame E in the extended position as shown in Fig. 1, 5 and the said supplemental leg frame may be also provided with swiveled hooks b^3 which may be turned to engage the inner faces of the upper portion of the main leg frame E as clearly shown in Fig. 6. It may be thus 10 seen that the supports of the table top will be rigidly held in both the extended and partially extended positions, and it may be further seen that the adjustment of these parts to the positions stated and also to fold 15 the supports, may be readily and easily accomplished by any one familiar with the operation. Attention should be further called to the fact that by the use of the connections as shown and described, an exceptionally flat and compact structure results 20 when the parts are folded to the positions shown in Figs. 4 and 5, in view of which the folded table may be readily handled and transported from place to place as desired.

25 I claim:

1. A folding and convertible table comprising a top, leg frames having hinged connections at their inner ends beneath the table top whereby they may be moved to positions against the under surface of the top 30 and at right angles with respect thereto, transverse strips carried by the said leg frames, a longitudinal bracing and connecting bar for the leg frames having notched

ends for engagement over the said transverse strips, hooks swiveled in the said connecting bar adjacent its ends and adapted for movement beneath the said transverse strips, and a hanger having a pivotal connection at one end intermediate the ends of the said connecting bar and pivotally supported at its opposite end beneath the said table top for the purpose described. 35

2. A folding and convertible table comprising a top, main leg frames beneath and 40 adjacent opposite ends of the top, supplemental leg frames hingedly connected to the under surface of the table top and to which the main leg frames are similarly connected, parallel bars pivotally connecting the said supplemental leg frames whereby to cause the same to move in similar directions, a transverse latch rod carried by the said parallel bars, a latch bar pivoted at one end 45 beneath the table top and having a recessed opposite end for engagement with the said transverse rod when the supplemental leg frames are in extended position, a member 50 for spacing and rigidly connecting the main leg frames, and means carried by one of the said supplemental leg frames whereby to lockingly engage the corresponding main leg frame when both the main and supplemental leg frames are in extended position. 55
